CLAIM

The ornamental design for a chair, as shown and described.

DESCRIPTION

FIG. 1 is a perspective view of a chair showing my new design;

FIG. 2 is a left side elevation view, the right side being a mirror image thereof;

FIG. 3 is a front elevational view;

FIG. 4 is a bottom plan view;

FIG. 5 is a top plan view; and,

FIG. 6 is a rear elevational view thereof.

A broken line showing support stretchers in FIGS. 1, 2, 3, 4 and 6 is for illustrative purposes only and forms no part of the claimed design.
